CLAIM

The ornamental design for a wheel balancer, substantially as shown and described.

DESCRIPTION

FIG. 1 is a typical side elevational view of a wheel balancer showing my new design with the suspension cable shown broken away for ease of illustration;

FIG. 2 is a side elevational cross-sectional view thereof as taken from line 2—2 of FIG. 1;

FIG. 3 is a top plan view as taken from line 3—3 of FIG. 1;

FIG. 4 is a bottom plan view thereof.

FIG. 3

FIG. 4
